UNITED STATES PATENT OFFICE

CLARENCE W. KUHN, OF MILWAUKEE, WISCONSIN, ASSIGNOR, BY MESNE ASSIGNMENTS, TO CUTLER-HAMMER, INC., A CORPORATION OF DELAWARE

MEANS FOR PROTECTING CONTACTS OF ELECTRIC SWITCHES

Application filed February 7, 1927. Serial No. 166,487.

This invention relates to improvements in means for protecting contacts of electric switches, and the invention more particularly relates to the provision of improved means for protecting relatively movable contacts of a switch from the destructive influence of arcs drawn therebetween.

It is customary to provide one or both of the relatively movable contacts of a switch with an arcing horn or shoe to receive and provide for disruption of the arc developed by opening of said contacts, an electromagnetic blow-out device being usually employed to effect or expedite passage of the arc from the contacts to the arcing horns. Moreover, such arcing horns have usually been formed of steel or brass, whereas in practice it is found that the contacts in conjunction with which such arcing horns are employed are subjected to severe destructive influences of the arc, so that the contacts rapidly become destroyed and must be frequently renewed.

I have discovered that by providing for shifting of the arc from one or both of the contacts to an arcing element or elements of relatively high melting point the vapor of which does not readily conduct the current the life and usefulness of such contacts will be very greatly increased, thereby minimizing the amount of time, labor and material required to keep the switch in proper working condition.

An object of the invention is to provide arcing elements of such character and construction as to greatly increase the life of switch contacts associated therewith.

Another object is to provide for utilization of a known commercial alloy in constructing said improved arcing elements.

Another object is to provide an improved structure of the aforementioned character which may be readily and economically manufactured.

Other objects and advantages of the invention will hereinafter appear.

The accompanying drawing illustrates certain embodiments of my invention which will now be described, it being understood that various changes in details may be made

without departing from the spirit and scope of the invention as defined by the claims.

In the drawing, Figure 1 illustrates the contacts of a conventional form of switch, said contacts having my improved arcing horns or elements associated therewith.

Fig. 2 is a similar view of a modification in which but one of my improved arcing elements is employed, and

Fig. 3 is a similar view of another modification embodying my invention.

Referring first to the device illustrated in Fig. 1, the numerals 5 and 6 designate the usual contacts of an electric switch, contact 5 being carried by a stationary support 7 and contact 6 being supported by member 8 for movement into and out of engagement with said contact 5. Member 8 is preferably so operated as to provide for final separation of contacts 5 and 6 at the tips 5^a and 6^a whereby the normal contacting surfaces thereof are protected to a certain extent from influence of the arc developed upon separation of the contacts. Electrically and mechanically united with each of said contacts is an arcing horn or element 9 of any usual or preferred form. Assuming provision of an electromagnetic blow-out device for the switch, the same is adapted upon separation of the contacts to transfer or shift the resulting arc from said contacts to the arcing elements 9, with consequent attenuation and extinguishment of the arc after a given time interval.

As aforeindicated, however, if the arcing elements 9 are formed in the usual manner from steel, brass or similar material it is found that the contacts are severely attacked by the arcs resulting from separation thereof, so that after service for a comparatively short time the same are rendered unfit for further use and must therefore be replaced by new contacts.

On the other hand if the arcing elements are formed of a material of the character disclosed herein it has been found that the life of such contacts is increased from fifty to one hundred per cent or more; thus achieving a desirable economy in the upkeep and repair of the switches. More specifically, the material of which the arcing elements are formed

preferably comprises an alloy composed principally of nickel and chromium, in the proportions of about eighty per cent nickel and twenty per cent chromium. This alloy is obtainable commercially, and one type thereof having nickel and chromium constituents in substantially the proportions aforementioned is known to the trade as "nichrome."

The reasons for the unusual success and advantages of arcing elements formed of this alloy are not definitely known, but it is noted that such material tends to expedite extinguishment of arcs drawn initially between the contacts upon opening of the latter.

In the device illustrated in Fig. 2 corresponding parts are given like characters of reference; whereas it will be noted that only the stationary contact 5 is provided with a so-called arcing element, thus requiring attenuation and extinguishment of the arc between the tip 6^a of contact 6 and the element 9. However, it is found that by forming element 9 of the aforescribed alloy of nickel and chromium the life of both contacts of the switch is materially increased or extended, as compared with that of contacts having the ordinary arcing element or elements associated therewith. The use of such alloy in this case likewise renders possible the more rapid extinguishment of the arc,—due probably to the resulting higher resistance value of the arc vapor.

Fig. 3 illustrates a modification wherein the supports 7 and 8 carry contacts 10 and 11, respectively, of slightly different construction. Thus said contacts may each comprise a body portion formed in the usual manner from copper or a copper alloy of relatively low resistance, whereas each of said contacts is provided with a tip 9^a of the aforesaid alloy. Thus upon opening of the contacts 10 and 11 the resulting arc will be initially drawn between the alloy tips or elements 9^a, so that the contacting surfaces of the contacts are unusually well protected from destructive influence of the arc. The tips 9^a are preferably integrally united with the body portions of the contacts 10 and 11 in any suitable or well known manner, as by welding or brazing. By employment of a device like that shown in Fig. 3 the necessity for the provision of separate arcing elements is obviated, whereas the over-all dimensions of the switch structure may consequently be somewhat reduced.

What I claim as new and desire to secure by Letters Patent is:

1. The combination with relatively movable switch contacts, of an arcing element associated with said contacts, said element comprising an alloy of nickel and chromium.
2. The combination with a pair of relatively movable switch contacts, of arcing elements associated with and electrically con-

nected to said contacts, said elements being composed of a nickel chromium alloy.

3. The combination with relatively movable switch contacts, of arcing elements therefor composed of the nickel chromium alloy "nichrome".

4. The combination with relatively movable switch contacts, at least one of said contacts having an arcing element mechanically and electrically connected thereto, said element comprising an alloy of about twenty per cent chromium and eighty per cent nickel.

5. The combination with relatively movable switch contact members, of arcing elements integrally united therewith mechanically and electrically, said elements consisting of the nickel chromium alloy "nichrome".

6. The combination with a pair of relatively movable switch contacts formed of conducting material of relatively low resistance, of arcing tips integrally united with said contacts by welding, said arcing tips consisting of an alloy of nickel and chromium.

In witness whereof, I have hereunto subscribed my name.

CLARENCE W. KUHN.
